UNITED STATES PATENT OFFICE.

HENRY A. KESSLER, OF BERKELEY, CALIFORNIA.

COMBINED POUCH AND CIGARETTE-MAKING DEVICE.

1,099,983.

Specification of Letters Patent. Patented June 16, 1914.

Application filed June 3, 1913. Serial No. 771,503.

To all whom it may concern:

Be it known that I, HENRY A. KESSLER, citizen of the United States, residing at Berkeley, in the county of Alameda and State of California, have invented certain new and useful Improvements in Combined Pouches and Cigarette-Making Devices, of which the following is a specification.

This invention relates to devices for making cigarettes and combined therewith a pouch to hold the tobacco and a holder for the cigarette papers, and has for one of its objects to simplify and improve the construction and increase the efficiency and utility of devices of this character.

Another object of the invention is to provide a simply constructed device whereby cigarettes may be manufactured one at a time as required.

With these and other objects in view the invention consists in certain novel features of construction as hereinafter shown and described and then specifically pointed out in the claims, and in the drawings illustrative of the preferred embodiment of the invention.

Figure 1 is a front elevation with the combined closure and rolling mechanism in open position. Fig. 2 is a section on the line 2—2 of Fig. 1. Fig. 3 is a view similar to Fig. 2 with the combined cigarette rolling and closure mechanism partly closed illustrating the action. Fig. 4 is a view similar to Fig. 1 with the combined closure and cigarette roller in closed position with the cigarette completed and ready to be discharged.

Corresponding and like parts are referred to in the following description and indicated in all the views of the drawings by the same reference characters.

The improved device comprises an upper body member 10 of sheet metal and preferably formed with a down-turned rim 11 to receive a tobacco holding pouch or bag 12, the latter being preferably of suitable fabric, but which may be of any other suitable material.

The member 10 is provided with a relatively large opening 13, and hinged at 14 to one side of the opening is a closure 15 which when turned down fills the opening 13. The closure 15 is provided with a relatively large opening 16 near its outer portion and with lateral flanges 17 at its sides, each flange being provided with a slot 18 extending for the major portion of its length in parallel rela-

tion to the faces of the closure, and curved away from the closure as shown at 19 next to the hinged edge. Slidably mounted within the slots 18 is a bar 20 having a fabric sheet 21 connected at one end thereto. The sheet is preferably of closely woven silk and is connected at its outer end at 22 to the closure 15 at the inner edge of the opening 16, the object to be hereafter explained.

Pivoted at 23 to the body 10 at its opposite sides are links 24, the links being coupled at their free ends to the bar 20. The links 24 will be so proportioned that when the member 15 together with its flanges 17 is disposed in its lowered position or within the opening 13 of the body 10, the bar 20 will be caused to move in the slots 18 toward the outer ends and stretch the fabric 21 between the bar 20 and the attaching point 21, the object to be hereafter explained.

Mounted to slide in the slots 18 by a central core 25 is a roller 26. Springs 27 connect the core 25 of the roller to the body 10 between the hinge 14 and the adjacent edge 80 of the body 10. The springs thus exert their pulling force against the roller to draw the latter toward the inner end of the slots 18. By reference to Fig. 2, it will be noted that when the closure 15 is located at right angles 85 to the body 10 the links 23 will hold the bar 20 and the roller 26 and its core 25 in the inner curved ends 19 of the slots 18 with the fabric 21 hanging downwardly between the closure 15 and the roller 26 forming a relatively large sack-like device.

The papers from which the closures or wrappers for the cigarettes are to be constructed are represented conventionally at 28 and are supported preferably in clefts in 95 a plate 28' which is attached at the body 10 to one side.

When the device is to be used one of the papers is removed from the member 28' and bent into U shape and inserted within the 100 bag-like fabric member 21 and the tobacco which is to form the core of the cigarette inserted into the interior of the paper through the opening 16, a relatively wide open space being produced by the curving 105 of the lower ends 19 of the slots 18, as will be obvious. The roller 26 is thus held initially against the outer face of the fabric 21 and the bar 20. The edge of the paper next to the roller is bent over the tobacco within 110 the paper envelop and forced for a short distance between the tobacco and the por-

tion of the fabric next to the inner face of the closure 15, thus starting the rolling action. The closure 15 together with its attachments is then moved into closed position, which action causes the links 23 to move the bar 20 toward the outer end of the slots 18 while the springs 26 draw the roller 25 in the opposite direction and against the outer face of the fabric 21 and compress the latter against the cigarette wrapper and causes the latter to roll around the tobacco and thus automatically "roll" the cigarette as the closure is moved toward the body 10. The natural swelling or bulging of the tobacco within the paper wrapper and the fabric sheet holds the roller 26 against the bar 25 and against the resistance of the spring 27, and thus imparts a constant pressure upon the tobacco. The bulging or swelling of the mass of tobacco within the fabric holding member prevents the roller from being moved into the curved portion 19 of the guideway so long as the cigarette material is located between the terminal 28 of the fabric material and the roller as shown in Fig. 3, and as the member 15 is moved toward its closed position the roller will impart a corresponding rolling motion to the paper inclosed tobacco forming the cigarette. When the member 15 is fully closed within the opening 13 the cigarette will have been completed and the roller drawn by the springs 27 into its initial position shown in Fig. 4. The cigarette can then be removed and the cover 15 again opened and another cigarette constructed as required.

The improved device is simple in construction, can be inexpensively manufactured and 40 of any suitable material and operates effectively for the purposes described.

Having thus described the invention, what is claimed as new is:

1. In a device of the class described, a support, a member movable upon said support, a flexible member connected at one end to said support and at the other end to said movable member, and a roller bearing against said flexible member.
2. In a device of the class described, a body member, a support movable on said body member, a bar movable upon said support, links connecting said bar to said body member, a flexible member connected at one end to said support and at the other end to said bar, a roller bearing against said flexible member; and springs connecting said roller to said body.
3. In a device of the class described, a body member, a support mounted to swing upon said body and provided with guide devices, a bar slidable in said guide devices, links connecting said bar to said body, a flexible element connected to said swinging member and to said sliding bar and adapted

to support a cigarette wrapper, a roller bearing against said flexible element, and springs connecting said roller to said support.

4. In a device of the class described, a body, a support mounted to swing upon said body and provided with guide devices curved away from the support at one end, a bar slidable in said guide devices and into the curved portions thereof, links connected to said bar and to said body, a flexible element connected to said swinging member and to said sliding bar and adapted to support a cigarette wrapper, a roller bearing against said flexible element, and springs connecting said roller to said body. 75

5. In a device of the class described, a body member, a support movable on said body member and having guideways, a bar movable in said guideways, links connecting said bar to said body member, a flexible member connected at one end to said support and at the other end to said bar, and a roller bearing against said flexible member. 85

6. In a device of the class described, a body member, a support movable on said body member and having guideways formed with straight and curved portions, a bar movable initially in the curved portions of said guideways and thence into the straight 95 portions of the same, means for connecting said bar to said body member, a flexible member connected at one end to said support and at the other end to said bar, and a roller bearing against said flexible member. 100

7. In a device of the class described, a receptacle including a top having an opening, a member mounted to swing upon said receptacle top and provided with flanges having guide slots and entering the opening of the receptacle top when the swinging member is closed, a bar slidable in said slots, links connecting to said support, a flexible element connected to said sliding bar and adapted to support a cigarette wrapper, a roller bearing against said flexible element and having journals engaging in said slots, and springs connecting said roller to said support. 105

8. In a device of the class described, a support, a member movable relative to said support, a flexible element connected respectively to said support and to said movable member, and a member bearing against said flexible element. 110

9. In a device of the class described, a support, a member movable relative to said support, a flexible element connected respectively to said support and to said movable member, a roller bearing against said flexible element, and means for yieldably holding said roller against said flexible element. 120

10. In a device of the class described, a support, a member movable relative to said 130

support, a flexible element connected respectively to said support and to said movable member, a member bearing against said flexible element, and means for yieldably holding said bearing member against said flexible element.

11. In a device of the class described, a support having an opening, a member movable past said opening, a flexible element connected respectively to said support and to said movable member, and a member bearing against said flexible element.

12. In a device of the class described, a support having an opening, a member movable past said opening, a flexible element connected respectively to said support and to said movable member, and means for yieldably holding said bearing member against said flexible element.

20 13. In a device of the class described, a

support having an opening, a member movable past said opening, a flexible element connected respectively to said support and to said movable member, a roller bearing against said flexible element, and means for 25 yieldably holding said roller against said flexible element.

14. In a device of the class described, a body, a support swinging upon said body, a member movable relative to said support, a 30 flexible element connected respectively to said support and to said movable member, and a member bearing against said flexible element.

In testimony whereof I affix my signature in presence of two witnesses.
